Primary Examiner — Mary Shannon Malley*Assistant Examiner* — Dustin Andrew Griffith(74) *Attorney, Agent, or Firm* — Banner & Witcoff, Ltd.(57) **CLAIM**

The ornamental design for a spectacle case, as shown and described.

DESCRIPTION

FIG. 1 is a front top perspective view of a spectacle case showing our new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the encircled portion 9 indicated in FIG. 1 and,

FIG. 10 is an enlarged view of the encircled portion 10 indicated in FIG. 2.

The long dash-short dash lines on FIGS. 1, 2, 9 and 10 represent the bounds of the enlargements taken from FIGS. 1 and 2, and form no part of the claimed design. The dash-dash broken lines depict portions of the spectacle case that form no part of the claimed design.

1 Claim, 10 Drawing Sheets(56)
